(57) **CLAIM**

The ornamental design for a cookie cage, as shown and described.

DESCRIPTION

FIG. 1 is an isometric view of a cookie cage showing our new design.

FIG. 2 is another isometric view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

In the drawings, the broken lines depict environment of the cookie cage and form no part of the claim.
